VILLIAM PARKIN, OF TAUNTON, MASSACHUSETTS, ASSIGNOR TO
REED AND BARTON, OF THE SAME PLACE.

Design No. 3,319, dated January 5, 1869.

DESIGN FOR A TAZZA FOR HOLDING CAKE.

The Schedule referred to in these Letters Patent and making part of the same

To all persons to whom these presents may come:

Be it known that I, WILLIAM PARKIN, of Taunton, in the county of Bristol, and State of Massachusetts, have invented or produced a new and ornamental Design for a Tazza for Holding Cake or other articles; and to hereby declare the same to be represented in the accompanying drawing, and to be thus described, such drawing being a photographic perspective side elevation of it.

The bowl *a* is elliptical or oval in top view, and has four elliptical shields, *b b b b*, arranged at the termini of its longitudinal and transverse diameters, there being a *bas-relief* of a helmeted head in each shield.

Between these shields is a milled border or rim, *c*, from which, and the two outermost shields, small knobs or balls *d d d d* may extend.

The bottom of the bowl is convex on its lower surface, and terminates in a convex centre piece, *e*, which rests on four curved legs, *f*, each of which terminates at its lower end in a horse's foot, *g*.

From the upper part of each of these legs a head, *h*, is extended.

The four legs are connected by a platform, *i*, arranged between them, as represented.

The said tazza may have a handle, *k*, applied to it, although it is intended to make it either with or without such.

When without it, the ears *l l*, which project from the middle shields, should be omitted.

The statuette of a greyhound, shown in the drawing, is not intended to constitute a part of the design.

I claim as my invention, the design of the bowl; also, that of the stand applied thereto, and arranged as represented.

WILLIAM PARKIN.
